LESLIE A. RAWSON, OF LOS ANGELES, CALIFORNIA, ASSIGNOR TO EMSCO DERRICK & EQUIPMENT COMPANY, OF LOS ANGELES, CALIFORNIA, A CORPORATION OF CALIFORNIA

OIL PUMPING APPARATUS

Application filed December 23, 1931. Serial No. 582,764.

My invention relates to oil pumping apparatus and is particularly adapted for use in the operation of oil well pumps such as are commonly used in the oil-producing industry for elevating the oil from the lower end of an oil well to the surface of the ground.

My invention has for its object to eliminate certain disadvantages of the present oil pumping apparatus, and in the elimination of such disadvantages my invention provides means whereby the sucker rod hanger may be adjusted horizontally on the walking beam in order that the sucker rod hanger may be positioned in vertical alignment with the upper end of the sucker rod.

In order that the features and advantages of my invention may be readily understood I will briefly refer to the practice in the oil-producing industry. During the drilling of an oil well it is common practice to perform the drilling operations without the presence of the walking beam, due to the fact that the walking beam would be in the way. After the well has been drilled, it is necessary to install the oil well pump and the apparatus for operating same. A Samson post is set up at one side of the derrick, and the walking beam is pivotally supported on the upper end of the Samson post. One end of the walking beam extends above the upper end of the oil tubing which extends into the well and above the sucker rods. The other end of the walking beam is connected to suitable apparatus whereby the walking beam is reciprocated. Since the Samson post is generally set up by workmen who are around the well at the time the pumping apparatus is installed, the Samson post is usually not accurately positioned, and the result is that the sucker rod hanger which is mounted on the end of the walking beam which extends over the oil tubing and sucker rod is not positioned in accurate vertical alignment with the sucker rods.

When the sucker rod hanger is not in correct vertical alignment with the sucker rods there is a side thrust imposed by the sucker rods against the stuffing box at the upper end of the oil tubing through which the sucker rods extend. The result of this is that

the stuffing box is unduly worn and is subject to leakage, and the sucker rod is continually flexed where it passes through the stuffing box and is liable to breakage.

My invention provides oil pumping apparatus which includes a supporting means for the sucker rod hanger whereby after the walking beam has been positioned on the Samson post, the sucker rod hanger may be adjusted in position so that the hanger is vertically aligned with the sucker rods.

A further object of my invention is to provide a means whereby the sucker rod hanger may be adjusted in position while the weight of the string of sucker rods and the pump plunger connected to the lower end thereof is supported by the walking beam. The advantage of such a construction is that adjustments of the sucker rod hanger for the purpose of obtaining alignment may be made without requiring the use of separate supporting means during the time that the adjustment is made.

A further object of my invention is to provide a combination of the character referred to in the above paragraph in which the pivot point of the sucker rod hanger is positioned above the adjustment means and close to a horizontal plane which extends through the pivot or fulcrum of the walking beam. The advantage of a construction by which this object is accomplished is that the pivot point is disposed so that when the walking beam is in a horizontal position or at the central part of its travel the pivot point for the sucker rod hanger is substantially in the same horizontal plane as the pivot point or fulcrum of the walking beam. By such an arrangement there is a minimum of deflection of the upper end of the sucker rods during the operation of the pumping apparatus.

It is a further object of my invention to provide in a pumping apparatus of the character outlined heretofore a separate means whereby the position of the sucker rod hanger may be adjusted.

Other objects and advantages of my invention reside in the details of construction of my invention. It is one of the objects of my invention to provide pumping apparatus

of the character mentioned in which the walking beam is provided with a pair of depending arms between which the sucker rod hanger and the adjustment means therefor are positioned. Another object of the invention is to provide a combination of the character mentioned in the preceding sentence in which the depending arms support a horizontal shaft or a support shaft on which the sucker rod hanger is adjustably supported between the depending arms.

Other objects which relate to the invention in general and which relate to the details of construction of the two forms of my invention to be described hereinafter will be emphasized in the following detail description of my invention.

In describing the details of my invention reference will be made to the accompanying drawings, in which,

Fig. 1 is a fragmentary elevational view showing the complete combination of the preferred form of my invention.

Fig. 2 is an elevational view taken as indicated by the arrow 2 of Fig. 1.

Fig. 3 is a sectional view taken as indicated by the line 3—3 of Fig. 1.

Fig. 4 is a sectional view taken as indicated by the line 4—4 of Fig. 2.

Fig. 5 is a sectional view illustrating an alternative form of sucker rod hanger which embodies the broad features of my invention.

Reference will now be made to the drawings in detail and the form of my invention disclosed in Figs. 1 to 4 inclusive will be described, whereafter the form of my invention shown in Fig. 5 will be described.

The numeral 11 represents an oil tubing which, according to standard well practice, extends downwardly through the well to a point below the oil level thereof, at which point there is secured thereto a pump barrel in which a plunger is reciprocated. Extending upwardly through the oil tubing from the pump plunger is a string of sucker rods 12. The sucker rods 12 extend through a stuffing box 14 provided at the upper end of the oil tube 11 for the purpose of preventing oil leakages. Connected to the oil tubing immediately below the stuffing box is the customary branch pipe 15 through which the pumped oil is conducted to a suitable oil reservoir.

In Fig. 1 the numeral 17 represents a Samson post. To economize space I have shown only the upper part of the Samson post, but it will be understood that this Samson post is of usual construction. Mounted on the upper end of the Samson post is a walking beam pivot or fulcrum 18, which pivotally supports a walking beam 19. The walking beam 19 extends rightwardly from the Samson post 17 and has an end 21 which is positioned above the oil tubing 11 and above the sucker rods 12.

Depending from the end 21 of the walking beam 19 is a pair of supporting walls or depending arms 22 and 23. These depending arms 22 and 23 are spaced apart in order to provide a recess 24, and in the preferred form of my invention these two depending arms are made integral with the end 21 of the walking beam 19 by oxyacetylene welding these arms to the end 21. It will be noted that these arms 22 and 23 are formed from plates which have edge walls which converge downwardly so that the lower ends of these depending arms 22 and 23 are relatively narrow at their lower ends.

Supported by the depending arms 22 and 23 is a support shaft or horizontal shaft 26, the ends of which rest in openings 27 provided in the depending arms 22 and 23. This supporting shaft 26 is locked in place by means of a nut 28 which is screwed onto the end of the supporting shaft 26 and which pulls a shoulder 29 of the supporting shaft 26 against the inner face of the depending arm 23. The function of this supporting shaft 26 is to support a hanger block 31 which constitutes a part of the sucker rod hanger of my invention. It will be noted that this supporting shaft not only occupies a substantially horizontal position when the walking beam is in a horizontal position, as disclosed in the drawings, but is also positioned so that its axis extends inwardly towards the fulcrum 18 of the walking beam 19.

The hanger box or hanger block 31 has a cylindrical opening 32 through which the supporting shaft 26 is extended. Since the supporting shaft 26 and the cylindrical opening 32 are of uniform diameter, the hanger block 31 may be moved laterally in the recess 24 provided between the depending arms 22 and 23. As disclosed best in Fig. 3, the hanger block 31 supports a bearing 34 which is mounted above the supporting shaft 26 and which extends horizontally at right angles thereto. The hanger block 31 provides an oil chamber 35 into which a lubricant is introduced through a suitable pipe 36. The bearing 34 extends through this oil chamber 35 and has openings 37 provided therein through which oil in the oil chamber 35 may reach the inner bearing surface of the bearing 34. Pivotally supported by the bearing 34 is a pivot shaft 38 which extends in a horizontal plane and at right angles to the supporting shaft 26. This pivot shaft 38 is preferably positioned so that it is in horizontal alignment with the fulcrum 18 when the walking beam is in a horizontal position, as shown in Fig. 1. The ends of the pivot shaft 38 project outwardly from the bearing 34, and the hanger block 31 and the ends thereof are received in the bosses 39 provided at the upper ends of arms 40 of a yoke 41. This yoke 41 which is open at its upper end conveniently surrounds the hanger block 31 and

the other parts of the invention. The yoke 41 and the pivot shaft 38 are connected together by suitable bolt connection 43 shown clearly in Fig. 3 of the drawings.

5 The lower part of the yoke 41 is provided with a clevis 44 to which the upper end of a supporting bar 45 is connected. The lower end of the supporting bar 45 is connected to an equalizing supporting means 46 which is 10 connected at its slower end to the sucker rods 12. The construction which joins the yoke 41 and the sucker rods 12 may be of any special or conventional design.

15 As emphasized in the introductory part of this specification it is desirable to have the sucker rod hanger in vertical alignment with the sucker rods. My invention provides means whereby the pivot shaft 38 may be laterally adjusted in order that it may be in 20 vertical alignment with the sucker rods 12. In the preferred form of my invention which is now being described, I provide an adjustment means which is embodied in the following construction.

25 Referring to Figs. 3 and 4 it will be noted that the hanger block 31 extends downwardly beyond the supporting shaft 26 in the form of a pair of depending lugs 48 having aligned openings 49. The lower ends of the depending arms 22 and 23 have openings 50 which are aligned with the openings 49. Extended through these openings 49 and 50 is a bolt 51 which serves the purpose of supporting the shims 52 which are placed between the depending arms 22 and 23 and side walls 54 of the hanger block 31. These shims 52 are used to fill the horizontal space between the side walls 54 of the hanger block 31 and the inner walls of the depending arms 22 and 23.

30 40 By placing the proper number of shims 52 on either side of the hanger block 31 the hanger block 31 may be properly positioned on the supporting shaft 26. When the shims 52 are properly positioned the bolt 51 is then 45 tightened in order that the shims will be held in place and will not be displaced. It will, therefore, be seen that by removing the shims 52 on the right of the hanger block 31 it would be possible to move the hanger block

50 55 31 in a rightward direction on the supporting shaft 26. This would provide a space at the left of the hanger block and in order to fill this space the shims removed from the right of the hanger block would be placed to the left of the hanger block, after which operation the bolt might be tightened and the hanger block 31 would be secured in its adjusted position.

It is believed that from the foregoing description the objects of my invention will be seen to be clearly accomplished by the construction just described. It is further believed that it will be quite obvious that the advantages attributed to my invention are 60 65 70 present in the construction just described.

It is particularly pointed out that not only is the hanger block 31 susceptible of adjustment in order that the pivot shaft 38 may be vertically aligned with the sucker rods 12, but this adjustment may be made during the time that the sucker rods 12 are supported by the end 21 of the walking beam 19. This is a very valuable feature of my invention.

75 In the first form of my invention just described, the adjustment means for the hanger block is made separate from the supporting shaft 26. This, however, is not essential, as will be obvious from an inspection of Fig. 5, in which an alternative form of my invention is disclosed. In Fig. 5, the supporting shaft 26 is provided with threads 55 and the cylindrical opening 32 of the hanger block 31 is provided with a threaded nut 56. This threaded nut 56 may be a separate part or it may be in the form of threads cut integral 80 with the walls of the hanger block 31 which surround the cylindrical opening 32. The right end of the supporting shaft 26 is provided with a polygonal head 57, whereby the supporting shaft 26 may be rotated by the application of a suitable wrench. It will be seen that by rotating the supporting shaft 26 it is possible to cause the hanger block 31 to travel in one direction or the other on the supporting shaft 26, thus repositioning the pivot shaft 38 with respect to the sucker rods 12. It will, therefore, be seen that in this second form of my invention the separate adjustment means is eliminated and the adjustment means is incorporated in the support means 85 90 95 of the invention.

100 The two forms of my invention it is believed are sufficient to illustrate that my invention is not limited to any one design or any two designs such as are disclosed and shown in the drawings of this application. My invention, to the contrary, is not limited to the structural forms disclosed and described herein but may be embodied in various other forms which embody the principles or important parts of my invention. I therefore desire that my invention be construed in accordance with the scope of the appended claims.

110 I claim as my invention:

115 1. In an apparatus for pumping oil from an oil well, the combination of: an oil tubing extended into a well; a sucker rod extending from said oil tubing; a walking beam pivotally supported with one end above said oil tubing; a horizontal supporting shaft supported by said end of said walking beam; a sucker rod hanger supported by said supporting shaft and supporting said sucker rod; and means for adjusting said sucker rod hanger on said supporting shaft.

120 125 130 2. In an apparatus for pumping oil from an oil well, the combination of: an oil tubing extended into a well; a sucker rod extending from said oil tubing; a walking beam pivot-

ally supported with one end above said oil tubing; a supporting shaft supported by said end of said walking beam; a sucker rod hanger supported by said supporting shaft 5 and supporting said sucker rod; and means separate from said supporting shaft for adjusting said sucker rod hanger on said supporting shaft.

3. In an apparatus for pumping oil from 10 an oil well, the combination of: an oil tubing extended into a well; a sucker rod extending from said oil tubing; a walking beam pivotally supported with one end above said oil tubing; a supporting shaft supported 15 by said end of said walking beam; a hanger block supported by said supporting shaft; a pivot shaft supported by said hanger block for supporting said sucker rod; and means for adjusting said hanger block on said supporting shaft.

4. In an apparatus for pumping oil from 20 an oil well, the combination of: an oil tubing extended into a well; a sucker rod extending from said oil tubing; a walking beam pivotally supported with one end above said oil tubing; a supporting shaft supported by 25 said end of said walking beam; a hanger block supported by said supporting shaft; a pivot shaft supported by said hanger block above said supporting shaft for supporting 30 said sucker rod; and means for adjusting said hanger block on said supporting shaft.

5. In an apparatus for pumping oil from 35 an oil well, the combination of: an oil tubing extended into a well; a sucker rod extending from said oil tubing; a walking beam pivotally supported with one end above said oil tubing; a supporting shaft supported by 40 said end of said walking beam; a hanger block supported by said supporting shaft; a pivot shaft supported by said hanger block for supporting said sucker rod; and means 45 separate from said supporting shaft for engaging said hanger block and for adjusting said hanger block on said supporting shaft.

6. In an apparatus for pumping oil from 50 an oil well, the combination of: an oil tubing extended into a well; a sucker rod extending from said oil tubing; a walking beam pivotally supported with one end above said oil tubing; a pair of spaced arms depending from said end of said walking beam; a supporting shaft supported by said pair of arms; 55 a hanger block supported by said supporting shaft; a pivot shaft supported by said hanger block for supporting said sucker rod; and means cooperating between said hanger block and at least one of said depending arms 60 for adjusting said hanger block on said supporting shaft.

7. In an apparatus for pumping oil from 65 an oil well, the combination of: an oil tubing extended into a well; a sucker rod extending from said oil tubing; a walking beam

pivotally supported with one end above said oil tubing; a pair of spaced arms depending from said end of said walking beam; a supporting shaft supported by said pair of arms; 70 a hanger block supported by said supporting shaft; a pivot shaft supported by said hanger block for supporting said sucker rod; and means cooperating between said hanger block and at least one of said depending arms for 75 adjusting said hanger block on said supporting shaft, said means including shims adapted to be placed between said hanger block and one of said depending arms.

8. In an apparatus for pumping oil from 80 an oil well, the combination of: an oil tubing extended into a well; a sucker rod extending from said oil tubing; a walking beam pivotally supported with one end above said oil tubing; a threaded supporting shaft rotatably supported by said end of said walking beam; a hanger block supported by said threaded supporting shaft, and having a threaded opening through which said threaded supporting shaft extends; pivot means 85 carried by said hanger block for supporting said sucker rod; and means for rotating said threaded supporting shaft for adjusting said hanger block on said threaded supporting shaft.

9. In an apparatus for pumping oil from 90 an oil well, the combination of: an oil tubing extended into a well; a sucker rod extending from said oil tubing; a walking beam pivotally supported with one end above said oil tubing; a supporting shaft rotatably supported by 95 said end of said walking beam; a hanger block supported by said supporting shaft; a pivot shaft supported by said hanger block for supporting said sucker rod; and means operable upon a rotation of said supporting shaft for adjusting said hanger block 100 on said supporting shaft.

In testimony whereof, I have hereunto set my hand at Los Angeles, California, this 17 day of December, 1931.

LESLIE A. RAWSON.
